UNITED STATES PATENT OFFICE.

ROBERT C. HAWLEY AND GEORGE E. HAWLEY, OF SOUTH BEND, INDIANA.

APPARATUS FOR HEATING GRAIN.

SPECIFICATION forming part of Letters Patent No. 394,267, dated December 11, 1888.

Application filed March 16, 1888. Serial No. 267,410. (Model.)

To all whom it may concern:

Be it known that we, ROBERT C. HAWLEY and GEORGE E. HAWLEY, citizens of the United States, residing at South Bend, in the 5 county of St. Joseph and State of Indiana, have invented a new and useful Improvement in Apparatus for Heating Grain, of which the following is a specification.

Our invention relates to an improvement 10 in apparatus for heating grain preparatory to grinding the same in mills; and it consists in the peculiar construction and arrangement of devices, that will be more fully set forth hereinafter, and particularly pointed out in the 15 claim.

The accompanying drawing is partly a vertical sectional view and partly an elevation of the grain-heating apparatus embodying our improvement.

20 A represents a heater or furnace through which extends a coil of pipe, B. From the upper end of the said coil, the said pipe extends in a vertical direction, as at C, and is provided at its upper end with a cylinder, D. 25 Communicating with the upper end of said cylinder and coiled around the same is a pipe, E, the lower end of which pipe communicates with the lower end of the coil B, and thereby forms a complete circuit through 30 which water may circulate.

F represents a reservoir, which is provided at its lower end with a pipe, G, that communicates with the pipe E.

H represents an outer shell or drum, which 35 envelopes the cylinder D and the coiled portion of pipe E, and is of greater diameter than the said coil, whereby a sufficient space is left between the outer shell and the coiled portion of the pipe E for the passage of grain.

40 The upper and lower ends of the said outer case or drum are conical in shape, as shown, and the upper and lower ends of the cylinder D are also conical in shape.

The interior diameter of the coiled portion 45 of pipe E is greater than the exterior diameter of the cylinder D, and the interior diameter of the casing H is greater than the exterior

diameter of the coil, and thereby space is left between said cylinder D and the coil and between the latter and the casing.

50

The upper and lower ends of the drum or case H are provided with openings I K, respectively, the latter being provided with a suitable cut-off valve, L.

The operation of our invention is as follows: 55 The valve L is closed, and the grain to be heated is poured into the drum or case H, and is thereby caused to surround the cylinder D and the coil of pipe E around said cylinder. A suitable quantity of water is supplied to 60 the pipe E from the reservoir, and as the water flows through the coil B it becomes heated by the fire in the furnace, and is forced upward into and through the cylinder D, and from the same through the surrounding coil 65 E, thereby maintaining the hot water in constant circulation, and consequently heating the coil E and the cylinder D, and thereby thoroughly heating the grain inclosed in the case or drum H around said cylinder and coil. 70 When the grain is sufficiently heated, the valve L is opened and the grain is discharged from the drum through the opening K.

Having thus described our invention, we claim—

75

The combination, in a grain-heater, of the vertical cylinder D, having the conical upper and lower ends to facilitate the passage of grain around said cylinder, the pipe E, communicating with the upper end of the cylinder and coiled around the same, the pipe C, extending from the lower end of the cylinder, the outer shell enveloping the cylinder and coil and having its upper and lower ends cone-shaped, and the valve in the lower end of the 85 shell, substantially as described.

In testimony that we claim the foregoing as our own we have hereto affixed our signatures in presence of two witnesses.

ROBERT C. HAWLEY.
GEORGE E. HAWLEY.
